UNITED STATES PATENT OFFICE

129,584

DESIGN FOR A SAFETY RAZOR BLADE

Louis C. Guertin, Worcester, Mass.

Application June 2, 1941, Serial No. 101,256

Term of patent 14 years

To all whom it may concern:

Be it known that I, Louis C. Guertin, a citizen of the United States, residing at Worcester in the county of Worcester and State of Massachusetts, have invented a new, original, and ornamental Design for a Safety Razor Blade, of which the following is a specification, reference being had to the accompanying drawing, forming part thereof.

Fig. 1 is a front view in elevation of the razor blade; and

Fig. 2 is an end view thereof, looking in the direction of arrow 2 in Fig. 1.

I claim:

The ornamental design for a safety razor blade, as shown.

LOUIS C. GUERTIN.
